CLAIM

The ornamental design for a flame diffuser insert for an immersion tube furnace, as shown and described.

DESCRIPTION

FIG. 1 includes a perspective view of a flame diffuser insert; FIG. 2 includes another perspective view of the flame diffuser insert;

FIG. 3 includes a side elevation view of the flame diffuser insert of FIG. 1;

FIG. 4 includes a cross-cut side view of the flame diffuser insert of FIG. 1;

FIG. 5 includes a top elevation view of the flame diffuser insert of FIG. 1; and,

FIG. 6 includes a bottom elevation view of the flame diffuser insert of FIG. 1.

The broken lines shown in FIGS. 1 to 6 are for the purpose of depicting portions of the flame diffuser insert and form no part of the claimed design.

1 Claim, 3 Drawing Sheets
